H. A. BEARD.
APPARATUS FOR CATCHING FALLING RAIN.
APPLICATION FILED JULY 11, 1912.

1,118,259.

Patented Nov. 24, 1914.

UNITED STATES PATENT OFFICE.

HERBERT A. BEARD, OF BEAUFORT, SOUTH CAROLINA.

APPARATUS FOR CATCHING FALLING RAIN.

1,118,259.

Specification of Letters Patent.

Patented Nov. 24, 1914.

Application filed July 11, 1912. Serial No. 708,749.

To all whom it may concern:

Be it known that I, HERBERT A. BEARD, a citizen of the United States, residing at Beaufort, in the county of Beaufort and 5 State of South Carolina, have invented certain new and useful Improvements in Apparatus for Catching Falling Rain, of which the following is a specification.

My invention relates to improvements in 10 apparatus for catching rain.

An important object of the invention is to provide means of the above mentioned character so constructed that the catchment receptacle thereof cannot be blown over and 15 will swing with the wind to be disposed at all times parallel to the direction of the falling rain.

A further object of the invention is to provide means of the above mentioned character, which is attractive in operation, the 20 same swinging in all directions with the wind and remaining parallel to the direction of the falling rain, thus indicating such direction.

25 Other objects and advantages of the invention will be apparent during the course of the following description.

In the accompanying drawings forming 30 a part of this specification and in which like numerals are employed to designate like parts throughout the same, Figure 1 is a central longitudinal sectional view through apparatus embodying my invention, parts being shown in elevation, Fig. 2 35 is a horizontal sectional view taken on line 2—2 of Fig. 1, Fig. 3 is a plan view of the gimbal joint structure removed, and, Fig. 4 is a similar view of a holding sleeve.

In the drawings, wherein for the purpose 40 of illustration is shown a preferred embodiment of my invention, the numeral 4 designates upstanding arms, having their upper ends bent inwardly and surrounded by a retaining ring 5. The upper ends of 45 the arms 4 are apertured, for receiving extensions or trunnions 6, formed upon an outer vertically swinging ring 7, included in a gimbal joint. This gimbal joint comprises an inner ring 8, provided with out- 50 wardly extending trunnions 9, disposed at a right angle to the trunnions 6 and serving

to pivotally connect the inner ring 8 with the outer ring 7, whereby the inner ring is free to swing at a right angle with respect to the movement of the outer ring, as is 55 customary in a gimbal joint structure. Arranged above the inner ring 8 in spaced concentric relation is a retaining ring 10, connected therewith by depending inclined legs 11, as shown. This retaining ring is 60 provided with a suitable number of openings 12, formed therein by bending its material outwardly, for receiving pins 13, formed upon a holding sleeve 14. This holding sleeve is arranged below the re- 65 taining ring 10, moved upwardly to pass the pins 13 through the openings 12 and then turn whereby the pins 13 will engage portions of the retaining ring 10.

Connected with and depending from the 70 holding sleeve 14 are vertical air vanes 15, preferably increasing in width downwardly and connected at their lower ends by a plate 16, as shown.

The numeral 17 designates a catchment 75 receptacle to be mounted within the holding sleeve 14, the same being provided at its upper end with an outwardly extending flange 18, as shown.

In operation, the arms 4 are vertically 80 arranged and held stationary by any suitable means. The wind by engaging the air vanes 15, will swing or shift the catchment receptacle, which is free to turn by virtue of the gimbal joint structure so that the 85 catchment receptacle is retained parallel to the direction of the falling rain.

It is to be understood that the form of 90 my invention herewith shown and described is to be taken as a preferred example of the same, and that various changes in the shape, size, and arrangement of parts may be resorted to without departing from the spirit of the invention or the scope of the subjoined claims.

Having thus described my invention, I 95 claim:—

1. Apparatus for catching rain, comprising a stationary upstanding post, a gimbal joint structure mounted thereon, a catchment vessel supported by one element of the gimbal joint structure, and air vanes con-

nected with the catchment vessel and disposed near the lower end thereof.

2. Apparatus for catching rain, comprising a stationary upstanding post, a gimbal joint structure mounted upon the post, a holding sleeve mounted upon one element of the gimbal joint structure, a plurality of air vanes connected with the lower end

of the holding sleeve, and a catchment vessel mounted within the holding sleeve.

In testimony whereof I affix my signature in presence of two witnesses.

HERBERT A. BEARD.
